GAME APPARATUS

Walter A. Tratsch and Bernhard C. Grunig,
Chicago, Ill.

Application May 15, 1935, Serial No. 21,494

2 Claims. (Cl. 194—1)

This invention relates to a game apparatus.

It is an object of this invention to provide an improved game apparatus which is relatively simple and inexpensive in construction and efficient in use.

Another object of this invention is to provide a game apparatus, of the so-called pin and marble type, embodying a ball elevating device, a coin slide, a runway for feeding spent balls to the elevating device, and a cut-off device for preventing the passage of balls from the runway into the elevating device when the coin slide is moved inwardly from coin-receiving position toward or into coin-discharging position.

Another object of the invention is to provide a cut-off device which constitutes an improvement over the cut-off device shown and described in the Paulin and Froom, Patent No. 1,938,495, issued December 5, 1933, on a Game apparatus.

A further object of the present invention is to provide a cut-off device which is moved into effective position, that is, into position to cut-off or prevent the passage of balls from the inclined runway to the elevating device, before the coin slide completes its inward movement or operative stroke, that is, before the coin slide moves the so-called "shuffle board" or ball-retaining member into ball-releasing position, as distinguished from the cut-off device in the Paulin and Froom patent, which is not moved into effective or cut-off position until the slidable ball retaining member is moved into ball-releasing position.

Another object of the present invention is to provide a cut-off device which is in no way associated with or operated by, the slidable ball-releasing member, as is the cut-off device in the Paulin and Froom patent, but which is, on the other hand, entirely independent of the ball-retaining member and is moved into effective position, by the action of the coin-controlled member, prior to the time the ball-retaining member is moved into effective or ball-releasing position.

Other objects will appear hereinafter.

The invention consists in the novel combination and arrangement of parts to be hereinafter described and claimed.

The invention will be best understood by reference to the accompanying drawings, showing the preferred form of construction and in which:

Fig. 1 is a fragmentary top plan view of a game apparatus embodying a preferred form of the present invention, showing part of the top wall

of the cabinet broken away to reveal the operating parts; and showing the cut-off device in its initial or ineffective position;

Fig. 2 is a view similar to Fig. 1 but showing the cut-off device in effective or operative position;

Fig. 3 is a view similar to Fig. 2 but showing the latching mechanism associated with the ball-retaining member in unlatched position;

Fig. 4 is a vertical sectional view on line 4—4 in Fig. 2; and

Fig. 5 is a vertical sectional view on line 5—5 in Fig. 3.

A game apparatus embodying a preferred form of the present invention is shown in the drawings, is therein generally indicated at 10, and comprises a cabinet 11 which includes an inclined playing board 12 having ball exit openings 13 therein.

Slidably mounted in the cabinet 11 below the inclined playing board 12 is a so-called "shuffle board" or ball-retaining member 14, which is provided with ball exit openings 15, and these ball exit openings 15 are adapted to be registered with the ball exit openings 13 in the inclined playing board 12, by movement of the ball-retaining member 14, so as to discharge the spent balls from the exit openings 13 below the inclined playing board 12 for return, by way of an inclined transverse runway 16, to a point 30 adjacent to or into the elevating device 17.

Slidably mounted in the lower end wall 18 of the cabinet 11 is a coin slide 19 which has a curved cam edge 27 at its inner end; this cam edge 27 being formed at one corner of the coin slide 19, at the intersection of the inner edge 28 thereof with one longitudinal edge 20 of the same. This cam or curved edge 27 of the coin slide 19 is engageable with an upstanding portion or arm 21 of a cut-off member 22, which is pivotally mounted in the cabinet 11, as at 23, by means of a laterally extending arm 24 which is attached to the cut-off member 22.

The cut-off member 22 projects through an opening 25 which is provided in a wall 29 which is arranged in the cabinet 11, and the cut-off member 22 has an angled arm 26 which is adapted to be projected across the inclined ball runway 16 to the elevating device 17; the cut-off member 22 being normally urged, by a spring 30, in a direction to dispose the angled end portion 26 thereof out of the ball runway 16.

Pivottally mounted in the cabinet 11, as at 31, is a latch member 32 which has a notched portion 33 and this notched portion 33 is engage-

able with a keeper plate 34 which is attached to the slide ball-retaining member 14 on the bottom side of the latter (Fig. 4), and a spring 42 normally urges the latch member 32 in a direction to dispose the notched portion 33 thereof in latching engagement with the keeper plate 34.

Pivotedly mounted in the cabinet 11, as at 35, is a bar 36 and carried by this bar 36, and depending therefrom, on the bottom side of the latter, is a lug or pin 37 which is adapted to engage the arcuate cam edge 38 of the latch member 32.

Likewise carried by the pivotal bar 36 on the bottom side of the latter is a pin or lug 39 which is engageable with a notched portion 40 which is provided in the coin slide 19.

The foregoing arrangement is such that when the coin slide 19 is pushed inwardly, the cam or curved edge 27 thereof engages the upstanding portion 21 of the cut-off member 22 and thereby pivots the cut-off member 22, against the action of its resetting spring 30, in a direction to dispose the angled arm 26 thereof across the inclined runway 16 at a point adjacent the lower end of the latter, so as to prevent balls from traveling down the runway 16 into the elevating device 17 when the coin slide 19 is moved from coin-receiving position.

It is to be noted that in the present game apparatus the cut-off member 22 is moved into effective or cut-off position, that is, the angled end portion or arm 26 of the cut-off member 22 is projected across the runway 16, prior to the time that the coin slide 19 moves the slide ball-retaining member 14 into ball-releasing position, as distinguished from the cut-off device in the Paulin and Froom patent, in which patent the cut-off device is not moved into operative or effective position until the slide ball-retaining member is moved into ball-releasing position; and it will also be noted that the cut-off device 22-26 of the present invention is entirely independent of the ball-retaining member 14 as distinguished from the cut-off device of the Paulin and Froom patent which is released for movement into effective position by operation of the ball-retaining member.

As the coin slide 19 is pushed inwardly (top to bottom, Figs. 1, 2 and 3) the notched portion 40 thereof engages the pin 39 which is carried by the bar 36 and thereby pivots the latter (clockwise, Figs. 1, 2 and 3). This movement of the bar 36 causes the pin 37 carried thereby to engage the arcuate cam edge 38 of the latch member 32 and thereby pivots the latter, against the action of its resetting spring 42, (clockwise, Figs. 1, 2, and 3) in a direction to release the notched portion 33 thereof from latching engagement with the keeper plate 34; and as the coin slide 19 continues to move inwardly the end portion 41 of the pivotal bar 36 engages the keeper plate 34 and thus pushes the slide ball-retaining member 14 into ball-releasing position.

By reason of the latching device 32-33-34 the player is prevented from fraudulently moving the ball-retaining member 14 into ball-releasing position without operating the coin slide 19, which might otherwise be accomplished by shaking the cabinet 11 back and forth in the direction of its long axis.

When the coin slide is retracted into its initial or coin-receiving position, the spring 42 again

acts upon the latch member 32 to engage the notched portion 33 thereof with the latch keeper 34, and the spring 30 acts upon the cut-off member 22-26 to retract the angled end portion or arm 26 thereof out of the runway 16 so that spent balls may be fed one at a time into the elevating device 17, it being understood that the purpose of the cut-off device 22-26 is to prevent the player from fraudulently operating the apparatus while holding the coin slide 19 pushed 10 in, that is, out of coin-receiving position.

While we have illustrated and described the preferred form of construction for carrying our invention into effect, this is capable of variation and modification, without departing from the 15 spirit of the invention. We, therefore, do not wish to be limited to the precise details of construction set forth, but desire to avail ourselves of such variations and modifications as come within the scope of the appended claims. 20

Having thus described our invention what we claim as new and desire to protect by Letters Patent is:

1. In a game apparatus, the combination of: a cabinet including a member providing a playing 25 surface and said member having a ball exit opening formed therein; means for projecting balls one at a time over said playing surface so that they may enter into said exit opening; means for elevating balls one at a time up onto said 30 playing surface from a point below the same; an inclined runway in said cabinet below said playing surface for conducting spent balls to said elevating means; means for temporarily retaining therein a ball which enters into said exit 35 opening; a coin-controlled member movably mounted in a wall of said cabinet and adapted to move said ball-retaining means into ball-releasing position; a cut-off member movably mounted in said cabinet and having a portion 40 movable into said runway to prevent the passage of balls down the latter to said elevating means; said second-named and coin-controlled member moving said cut-off member into effective position to prevent the passage of balls down said 45 runway to said elevating means prior to the time said ball-retaining means is moved into ball-releasing position; means normally latching said ball-retaining means against movement, and means coacting with said second-named and coin-controlled member for moving said latching means out of latching engagement with said ball-retaining means and for moving said ball-retaining 50 means into ball-releasing position after said cut-off member has been moved into effective or 55 ball-releasing position.

2. In a game apparatus, the combination of: a cabinet including an inclined playing board having a ball exit opening therein; a member slidably mounted in the said cabinet below said 60 playing board and adapted to temporarily retain therein a ball which enters into said exit opening; means normally latching said second-named and ball-retaining member against operation; a lever for releasing said latching means, and a 65 coin-controlled member slidably mounted in a wall of said cabinet for operating said lever to release said latching means from latching engagement with said ball-retaining member and for moving the latter into ball-releasing position. 70
